HYDRAULIC ACCELERATION INTEGRATOR
SWITCHWilliam B. McLean, Washington, D. C., assignor
to the United States of America as represented
by the Secretary of the Navy

Application June 24, 1946, Serial No. 678,756

5 Claims. (Cl. 200—52)

(Granted under the act of March 3, 1883, as
amended April 30, 1928; 370 O. G. 757)

1

This invention relates to acceleration integrators for establishing a time interval which is a function of the acceleration of the whole mechanism, and more particularly to a novel hydraulic acceleration integrator for this purpose.

An object of the invention is the provision of an acceleration integrator in which a movable weight responsive to the acceleration of the entire apparatus traverses an oil-filled chamber from which the oil is extruded through a series of orifices.

Another object is the provision of means for biasing the weight against gravity to enable a function of the acceleration to be integrated.

Another object is the provision of combined spring and solenoid-operated means for resetting the integrator.

These and other objects of the invention may be better understood by reference to the accompanying drawing, in which:

Fig. 1 is a longitudinal sectional view of one form of the new integrator, showing the positions of the parts after operation of the integrator, and

Figs. 2 and 3 are sectional views on the lines 2—2 and 3—3, respectively, in Fig. 1.

The device as shown comprises a main cylinder 1—1a having its ends closed by a head 2 at one end and a head 3 at the opposite end, the latter head having a threaded integral nipple 4 extending centrally therefrom. Surrounding the nipple 4 and in threaded engagement therewith is a cylindrical insulating member 5 having its inner wall threaded to receive a sleeve 6. The inner wall of the latter is threaded to receive a threaded plug 7 of insulating material which is moved vertically according to the rotation given a shaft 8 having a square end 8a fitting into a similarly shaped recess in the plug 7. A cap 9 maintains the alignment of shaft 8, and a knurled disk 10 facilitates the turning of shaft 8 by hand.

The cylindrical member 5 has an inner bore 11 aligned with the nipple portion 4, the latter, having a bearing 12, receives a rod 13. The rod 13 has a head or enlargement 14 at its upper end and passes through and is united to a piston 15 near its lower end, as by a pin 15b. The piston defines the bottom of a chamber A in the upper portion of cylinder 1. The extremity 16 of rod 13 overlies a central aperture D in a movable solenoid core 17 which is moved downward upon energization of a surrounding solenoid 18. The solenoid is adapted to be energized by the closure of a simple operating circuit such as G. A cylinder 19 in the solenoid serves as a guide for the core 17 and is held in alignment by a

shouldered ring 20, which joins the cylindrical sections 1 and 1a, and by a conical-ended, stationary solenoid core 21 screwed into the head 2. The cylinder 19 has a cap 19a which, with the cylinder 19 and the upper end of movable core 17, defines an annular chamber C around rod 16 when the parts are in their final positions as shown. At its lower end portion, the core 17 is reduced to form an annular chamber E around the core parts 17, 21, the chamber E communicating through passages 22 in the core 17 with the chamber C. A spring 23 in chamber E normally urges the movable core 17 upward against rod 16.

15 The lower end portion of piston 15 is provided with an annular chamber B which communicates through passages 15a in the piston with the upper chamber A. A compression spring 24 in the chamber B normally urges the piston 15 upward to counterbalance the effect of gravity on the piston.

In the normal condition of the apparatus, the solenoid 18 is deenergized and the piston 15 is held in its uppermost position, in which head 25 14 engages plug 7, by the combined action of springs 23 and 24, the spring 23 acting through core 17 against the lower end of rod 13. In this position of the parts, the volume of chamber A is considerably smaller than shown since the piston 15 is raised from the ring 20, and the volume of chamber C is considerably smaller than shown because the movable core 17 is raised from the fixed core 21. The chamber A, passages 15a, chamber B, and the space directly under the 30 raised piston 15 are filled with oil. Similarly, the chamber C, passages 22, chamber E, aperture D, and the space directly under the raised core 17 are filled with oil.

In operation, the cylinder 1—1a is accelerated 40 upwardly, as seen in Figure 1. The integrator becomes subject to that acceleration by virtue of being mounted, for example, in a bombing airplane. When so mounted the integrator functions as an element in toss bombing and may be 45 used in a method of bombing such as disclosed in an application for patent of Harold S. Morton, for Bombing Method, filed June 1, 1944, Serial No. 538,311. That use will occur when the attacking airplane is made to pull up sharply as a preliminary to the release of a bomb, whereupon desiring to integrate the upward acceleration of the airplane the solenoid 18 is energized by the closure of the operating circuit G to lower the core 17 from the lower end of rod 13, thereby 50 compressing the spring 23. During this action, oil 55

is displaced from chamber E and the space between the cores 17 and 21, into the chamber C. Thereupon, the piston 15 will move downwardly against spring 24, due to the setback force on the piston incident to the acceleration, and force oil through the openings 15a into the upper chamber A, until such time as the head 14 contacts the inwardly projecting lip 6a of the sleeve 6 to complete an electric relay circuit R, the purpose of which circuit is to close a bomb release circuit F. From this it will be understood that the piston becomes instrumental in delaying the release of the bomb during the acceleration of the airplane until the proper bomb velocity has been reached. The rate of flow of oil through the orifices 15a will be proportional to the acceleration and the total flow quantity will be proportional to the integral of the acceleration. It will be apparent that as the acceleration is increased, the time interval from energization of solenoid 18 to closing of contact 14-6a will be decreased, due to the greater force of setback on piston 15 and therefore its faster downward movement through the oil. Adjustment of the stop plug 7 will vary the starting point of the piston 15 and consequently the stroke of the piston assembly, as required. In other words, the result of the integration is to release a bomb when the upward velocity of the airplane has changed by an amount set by the movable contact 14. Provision of the spring 24 to support part of the weight of the piston 15 allows the integration of a function of the form $a(K-b)$, where a and b are constants and K is the acceleration of the mechanism. In the formula stated, a equals mass, K equals acceleration of the airplane, b equals the counterforce exercised by the spring. Briefly applying this formula, the velocity of the piston 15 in the cylinder I depends on the force exerted on the oil by the piston. This function is a function of the mass and the accelerating force on it. Therefore, the force exerted by the piston is proportional to the product of the mass and accelerating force. The value of the accelerating force is K minus b . From this it is seen that the total accelerating force is K minus b plus the total force by the piston on the oil, in other words $a(K-b)$. Packing at 26 prevents passage of oil above this point while maintaining at constant volume the chambers into which oil is permitted to flow, irrespective of the position of the plug 7.

It will be understood, of course, that the apparatus shown will be maintained at a constant temperature during use to eliminate viscosity variation in the oil used.

The acceleration integrator is automatically reset upon deenergizing of the solenoid 18. At that time, the springs 23 and 24 return the parts to their initial positions, with the head 14 engaging plug 7, and with the core 17 engaging rod 13. During this return movement, the oil is displaced by a reversal of the flow previously described.

The invention herein described may be manufactured and used by or for the Government of the United States of America for governmental purposes without the payment of any royalties thereon or therefor.

I claim:

1. In a device for obtaining the time integral of acceleration perpendicular to the line of flight of a bombing aircraft preliminarily to the release of a bomb therefrom, a cylinder containing a hydraulic fluid, a piston in the cylinder having

a passage therethrough, the piston being movable in the cylinder to displace said fluid through said passage in response to acceleration of the cylinder, means normally securing the piston against movement in the cylinder, means for releasing said last means and thereby to establish the beginning of a time interval, and means operable by the piston for establishing the end of said time interval.

2. In a device for obtaining the time integral of acceleration perpendicular to the line of flight of a bombing aircraft preliminarily to the release of a bomb therefrom, a cylinder containing a hydraulic fluid, a piston in the cylinder having a passage therethrough, the piston being movable in the cylinder to displace said fluid through said passage in response to acceleration of the cylinder, spring-pressed means normally securing the piston against movement in the cylinder, electromagnetic means for rendering said last means inoperative to secure the piston and thereby establish the beginning of a time interval, and contact means operable by the piston for establishing the end of said time interval.

3. In a device for obtaining the time integral of acceleration perpendicular to the line of flight of a bombing aircraft preliminarily to the release of a bomb therefrom, a cylinder containing a hydraulic fluid, a piston in the cylinder having a passage therethrough, a ring in the cylinder intermediate its ends, a spring seated on the ring and normally urging the piston away from the ring, the piston being movable toward the ring against the spring to displace said fluid through the cylinder in response to acceleration of the cylinder against the piston, a rod on the piston having a contact head, a stop against which said head is urged by the spring and adjustable to vary the normal position of the piston, a solenoid in the cylinder, a fixed core in the solenoid, a movable core in the solenoid having a recess therethrough, a spring urging the movable core away from the fixed core and against said rod to supplement the action of said first spring in urging the piston away from the ring, the solenoid being operable to move said movable core toward the fixed core to release the rod and establish the beginning of a time interval, thereby displacing said fluid through said recess, and the piston upon release of the rod being movable to displace said fluid through the piston passage in response to acceleration of the cylinder, and a fixed contact on the cylinder engageable by said contact head of the rod upon said movement of the piston to establish the end of said time interval.

4. A device for obtaining the time integral of acceleration perpendicular to the line of flight of a bombing aircraft preliminarily to the release of a bomb therefrom, said device having a closed cylinder containing a hydraulic fluid, a piston fitting the cylinder, said piston having a passage therethrough and being movable in one direction by set-back to displace the fluid through the passage in proportion to the acceleration of the aircraft, a spring acting on the piston normally counterbalancing a fraction of the force of gravity thereby making the set-back movement of the piston solely expressive of the value of the acceleration of the aircraft, and electrical contacts for a bomb release circuit, being closed by the piston at the end of its set-back movement.

5. A device for obtaining the time integral of acceleration perpendicular to the line of flight of a bombing aircraft preliminarily to the release of

a bomb therefrom, said device having a closed cylinder containing a hydraulic fluid, an inertia-operable circuit closer including a piston fitting the cylinder and having a passage therethrough for the displacement of the fluid in proportion to the acceleration of the aircraft, means partially counterbalancing the piston against gravity thereby making the set-back movement of the piston solely expressive of the value of the acceleration of the aircraft, and predeterminedly spaced electrical contacts for a bomb release circuit, being moved toward each other by said inertia-operable closer and engaged to close the circuit after a period of acceleration proportioned to the spacing of the contacts.
